UNITED STATES PATENT OFFICE.

HOWARD J. MURPHY, OF READING, MASSACHUSETTS, ASSIGNOR, BY MESNE ASSIGNMENTS, TO THE BASSICK MANUFACTURING COMPANY, OF CHICAGO, ILLINOIS, A CORPORATION OF DELAWARE.

LUBRICATING SYSTEM AND APPARATUS.

Application filed March 14, 1922. Serial No. 543,654.

This invention pertains to improvements in lubricating apparatus. It is among the objects of the invention to improve lubricating apparatus wherein a source of lubricant under pressure may be connected to and disconnected from a lubricant-receiving part. The improvements relate primarily to the lubricant-receiving part or nipple and to the coupling and valve-operating mechanism for use in connection therewith.

In the drawings which show a preferred form of one embodiment of my invention:—

Figure 1 is a longitudinal, central section through a preferred form of lubricant-ex- 15 pelling device, being partly in elevation;

Fig. 2 is a central, longitudinal section through the coupling end of the device, showing the parts in their relationship prior to coupling;

Fig. 3 is a section similar to Fig. 2, but showing the lubricant-receiving nipple and the relative position of the parts pursuant to the coupling and valve-opening operations;

Fig. 4 is a view showing an elevation of a portion of the parts shown in Fig. 3, in their coupled relation;

Fig. 5 is a section on the lines 5—5 of Fig. 4;

Fig. 6 is a section on the line 6—6 of Fig. 3; and

Fig. 7 includes an end and a side elevation, and central, longitudinal section of a preferred form of lubricant-receiving nipple.

Referring to the drawings and to the preferred form of my invention selected for illustrative purposes, I have shown a lubricant-receiving nipple presenting adjacent the lubricant-receiving end thereof a generally triangular portion presenting three underlying surfaces which may be engaged by cooperating coupling parts, such surfaces being of very considerable area without unduly increasing the over-all cross-sectional dimensions of the nipple at this point.

What would be the corners of a triangle formed by these projections are preferably omitted, what would otherwise correspond to the corner portions being preferably rounded so that the cross-section of the nipple at this point is six sided while generally

triangular because three of the sides are considerably longer than the three other sides.

Aside from the extended underlying surfaces and great strength of the generally triangular form of the nipple at these projections, I have found that three-point support is of decided advantage in connection with a coupling, insuring an even bearing.

55 Of even greater advantage is the fact that the triangular construction provides long lateral faces generally at acute angles to

each other, which serve as guiding faces facilitating the entrance of the portion 60 under consideration into an aperture of a cooperating coupling. This is of particular

advantage in connection with a lubricating system of the preferred form, wherein the coupling is carried directly by a lubricant- 65

expelling device such as a lubricant gun as distinguished from being carried by a flexible coupling or the like, and especially where coupling may be effected while holding the 70 gun at its end opposite that on which the

coupling is provided and at a point considerably removed from the lubricant-receiving nipple. Not only are the length of the 75 faces of the nipple of advantage during this entering operation; but the disposition of

adjacent faces at acute angles to one another provides a marked advantage over 80 such faces at right angles to one another, as in a square, or at obtuse angles to one

another, as in a cross-section providing more 85 than four symmetrically arranged sides. The removal or omission of the corners also

greatly facilitates the entering operation and, where a round guiding portion is 90 provided in advance of the projections on the nipple, such round or cylindrical portion

approximately fitting between the faces of the adjacent coupling opening, the engagement of the coupling with the lubricant-receiving 95 nipple is so readily effected as to be

almost automatic.

In the preferred form of nipple hereinbefore described, and best shown in Fig. 7, the nipple 8 is provided with three projections 9, 9, 9 above referred to, each rounded 100 and connected by the three surfaces 10, 10,

10 at acute angles to each other and rela-

tively long. The projecting portion 11 facilitating entrance is preferably, as illustrated, substantially in tangential relation to the three straight sides 10 of the projecting portions of the nipple, as is also the body portion of the nipple lying below or beyond the projections thereon.

Cooperating with the preferred form of nipple, I have shown lubricant-expelling means including the barrel 12 provided with a rear head 13 into which is threaded a stem 14 carrying a plunger 15. The preferred form of plunger illustrated includes a cup washer 16 held in expanded position by spring fingers 17 projecting from a contained disc lying beneath a reinforcement 18 through which the stem 14 is riveted.

In the preferred form of my invention illustrated, the rear head 13 is constructed with a sufficiently deep recess to receive the plunger 15 including the leather cup 16 so that, when the plunger is entirely retracted and the head removed, no difficulty will be experienced in again entering the plunger in the barrel 12, this because the recess in the head 13 aligns with the opening in the barrel 12.

In the preferred form of my invention illustrated, I have shown the coupling cooperating with a valve, these parts being carried within the end of the barrel 12 preferably by interengaging threads 20, and I have found it convenient, to prevent tampering with the coupling and valve mechanism, to spin over the end of the barrel at 21 to hold the coupling and valve parts in position. This spun-over portion 21 also acts as a seal whereby, if the mechanism has been tampered with, such tampering will be evidenced even though done by a skilled mechanic.

The preferred form of coupling illustrated includes a retractile coupling sleeve 30 cooperating with a sealing part 31, preferably presenting, as illustrated, a sealing washer 32, the sealing part 31 and retractile sleeve 30 being interconnected by pin and slot means typified by the pin 33 and the slot 34. To provide a preferred form of deferred valve mechanism, the retractile sleeve 30 and sealing part 31 are both mounted for movement relative to the barrel of the gun 20, and to this end I have provided a front head 35 for the gun exteriorly threaded at 20 to fit corresponding threads on the interior of the gun barrel and, between a projection 36 on this head and the retractile sleeve 31, I have provided valve-operating pin and slot means typified by the pins 37, 38 and cooperating slots 33, 38.

Carried by the sealing part 31, I have provided a longitudinally movable valve 39 adapted to cooperate with a seat carried by the head 35 and apertured to permit, when open, the passage of lubricant therethrough

into the grease-delivering aperture 40 in the sealing part 31. The head 35 is provided with a cylindrical extension presenting exteriorly an elongated guiding surface over which the retractile sleeve 30 may move during the coupling and valve-actuating operations. I have recessed the front end of the projection 36 at 41 to admit a rearwardly extending cylindrical part 42 of the sealing part 31 and I have provided an interposed spring-pressed cupped sealing washer 43 to seal the joint between the part 42 and projecting portion 36 while permitting sliding movement. The end of the retractile coupling sleeve 30 is apertured to receive an end of the lubricant-receiving nipple including the projections thereon, and provides three flanges 50 which underlie the triangular projections on the nipple pursuant to the coupling operation. Within the retractile coupling sleeve 30, I have provided a connecting sleeve 51 similarly apertured and of sufficient length to engage a projecting part 52 on the sealing part 31 which is of irregular cross-section and preferably generally triangular to correspond to the cross-section of the part of the nipple 8 having the projections.

In the preferred form of my invention illustrated, it is particularly desirable to provide for completion of the coupling operation prior to initiation of the valve opening operation and to provide for closure of the valve prior to initiation of the uncoupling operation. To this end the valve opening slot 38 is provided with a relatively abrupt angle portion 60 in which the valve-operating pin 37 remains precluding turning movement of the retractile sleeve 30 relative to the head 35 of the gun until after a certain amount of retractile movement of said sleeve has taken place, such retractile movement being sufficient to move together the flanges 50 and the sealing washer 32 on the sealing part 31 to provide a tight joint around the lubricant-delivering passage 40 in the sealing part 31. The retractile coupling sleeve 30 is normally pressed towards its advanced or uncoupled position by a spring 60 interposed directly between such sleeve and the head 35. Because of the action between the retractile sleeve 30 and the sealing part 31 by the pin and slot connection, this spring 60 also tends to press the valve 39 against its seat. To further guide and align the retractile sleeve 30 and to prevent tampering with and to keep dirt out of the interior mechanism, I have provided an external sleeve 61, screw-threaded at 62 into the interior thread on the barrel 12, and it is preferably over this exterior sleeve or cover that the spun-over portion 21, serving as a seal, is provided.

To prevent opening of the valve pursuant to pressure on the end of the retractile sleeve 130

30, when uncoupled, the slot 34 is extended downwardly at 63 (Fig. 4) so that if the sleeve 30 is pressed rearwardly, no resultant movement of the valve 39 will take place, the movement in question being taken up and limited by movement of the screw 37 from the sharply inclined end 60 thereof to the position illustrated in Fig. 4 against the opposite wall so that no resulting opening of 10 the valve is effected.

Assuming the nipple to be entirely removed from the coupling, the coupling parts will occupy the relative position illustrated in Fig. 2, the opening in the end of the 15 retractile sleeve 30 coinciding with the opening in the connecting sleeve 51. If now the nipple be entered and the gun turned in clockwise direction, as viewed from the right of Fig. 1, the sleeve 51 and the sealing part 31 cannot turn because held against rotation by the projections on the nipple, the nipple being fixed to a part to be lubricated. The 20 sleeve 30 may, however, turn and will turn to bring the projections on the nipple over 25 the flanges 50 on the retractile sleeve. During this turning movement, the retractile sleeve will be retracted because of the inclined slot 34 which will have been turned relative to the pin 33, which is held stationary in the sealing part 31. During this 30 initial coupling movement, the valve cannot have been opened because the pin or screw 37 is entered in the steep part 60 of the slot 38. During this retractile coupling movement, however, the pin 37 will have moved 35 to a point past the corner between the abrupt and inclined portions of the slot 38, so that by the time the head of the nipple is sufficiently pressed against the sealing disc 40 32 to provide a tight joint, the pin or screw 37 will have come down sufficiently so that the rounded part thereof may pass the adjacent corner in the slot 38.

Further turning of the barrel in clockwise direction as viewed from the right of Fig. 45 1, will result in turning of the head 35 of the gun, carrying the pin 37, without a corresponding turning movement of the retractile sleeve 30. This relative turning movement will cause the head of the barrel to be drawn forward (with the barrel and exterior sleeve 61), while the sealing part 31 remains stationary, fixed relative to the retractile sleeve 30. The valve 39 will also remain stationary with the sealing part 31 and, as the head 35 moves forward, its seat will be drawn away from it, opening the valve and permitting flow of lubricant therethrough to the lubricant-receiving nipple. The 50 spring 60, initially somewhat compressed during the coupling operation, has been further compressed during the valve-opening operation and the inclination of the slots 34 and 38 is such that, after the desired lubrication has been effected, the barrel is

turned counterclockwise as viewed from the right of Fig. 1, and the pin 37 will return to the position shown in Fig. 4 of the drawings, thus closing the valve before any turning movement of the retractile sleeve 30 initiates the uncoupling operation and withdrawal of the sealing washer 32 from its position where it is pressed against the lubricant-receiving end of the nipple 8.

The parts are preferably so proportioned 75 that the screw 33 will never normally reach the end of the slot 34 and for this reason, where the coupling in question is used in connection with a screw-actuated lubricant gun, torque on the gun arising from the lubricant-expelling operation will constantly tend to 80 tighten the joint so that the greater the pressure, the greater the seal.

The sealing washer 32 may be entirely back-supported by the sealing part 31 or a 85 recess may be provided, as illustrated, behind the sealing washer to permit the lubricant by its pressure behind the sealing washer to exert pressure on the latter against the head of the lubricant-receiving nipple around the 90 lubricant-receiving aperture therein. Where the pressure of the lubricant is availed of to supplement the pressure of the inclined slot and pin cooperating to effect the coupling, a tight seal will be provided even though 95 by lateral pressure on the gun barrel or handle the gun is kept out of alignment with the nipple, which, in the absence of the grease-pressed seal might prevent the coupling from effecting an absolutely tight seal 100 against great pressure.

While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

I claim:

1. A lubricant gun presenting a barrel having at its discharge end a coupling comprising unitary valve and sealing means, said means extending into said barrel, a protective sleeve surrounding said means, and a flanged over portion of said barrel for retaining said sleeve and means in their respective positions, said flanged over portion and sleeve serving to prevent tampering with said valve and sealing means.

2. A lubricant gun presenting a barrel, a discharge head entered in said barrel and engaged with the interior thereof, a nozzle sleeve having an end also entered in said barrel, said head and nozzle sleeve carrying coupling means and valve means controlling discharge of lubricant from said barrel.

3. A lubricant gun having a barrel closed by a head adjacent its discharge end and providing coupling means including a re-

tractile sleeve having means for coupling engagement with a lubricant receiving nipple, and a compression spring acting upon said sleeve and normally serving to maintain it in extended position.

4. Lubricating apparatus comprising, in combination, a supply barrel having a valved coupling at the discharge end thereof, said coupling member presenting a retractile terminal part for coupling engagement with a lubricant receiving nipple, a valve openable by forward movement of said barrel relative to said terminal part, and unyielding means precluding opening of said valve by forward movement of said barrel relative to said terminal part prior to the coupling operation.

5. Lubricating apparatus comprising, in combination, a supply barrel having a valved coupling at the discharge end thereof, said coupling presenting a retractile terminal part, a valve openable by forward movement of said barrel relative to said terminal part, and pin and slot means precluding opening

of said valve by forward movement of said barrel relative to said terminal part prior to the coupling operation.

6. Lubricating apparatus comprising, in combination, a supply barrel having a valved coupling at the discharge end thereof, said coupling presenting a terminal portion having flanges to underlie projections on a lubricant receiving part, a sealing part, incline means directly interposed between said terminal part and said sealing part to effect approaching movement between said flanges and said sealing part, said sealing part carrying a washer for engagement with the lubricant receiving end of the lubricant receiving part, and a recess in said sealing part behind said washer to permit the pressure of the lubricant to move or flex said washer and compensate for any absence of alignment of the axis of said lubricant receiving part with the axis of said coupling.

In testimony whereof, I have signed my name to this specification.

HOWARD J. MURPHY.
